(57) **CLAIM**

The ornamental design for an operational face plate cover for a vertically movable vending machine, as shown and described.

DESCRIPTION

FIG. 1 is a front elevation view of an operational face plate cover for a vertically movable vending machine, showing my design;

FIG. 2 is a right side elevation view thereof;

FIG. 3 is a left side elevation view thereof;

FIG. 4 is a top plan view thereof; and,

FIG. 5 is a bottom plan view thereof.

In the drawings the broken lines illustrate environment and form no part of the claimed design.
